UNITED STATES PATENT OFFICE.

DANIEL SHONQUIST, OF TAMPICO, MEXICO.

TOOL-HOLDING DEVICE.

Application filed October 6, 1923. Serial No. 667,004.

This invention relates to improvements in tool holding devices and particularly to devices for holding drilling tools, such as used in drilling oil wells and the like.

5 In the operation of drilling through the earth's surface for oil it is usually necessary to drill a considerable distance into the earth and it is desirable to minimize the wear on the wire rope or other operative 10 connection between the drilling tool at the bottom of the well and the source of power located on the surface of the ground to keep sand or other deleterious material from entering the tool joint threads and injuring 15 the same.

One of the objects of the present invention is to provide an improved tool holding device in which the wire rope is protected from excessive wear and thus increase its 20 life.

Another object relates to minimizing the play between the several parts of the device whereby distortion of certain of the 25 parts is effectively prevented.

Another object relates to the provision of a tool socket which may be made either stiff or swivelling, as may be desired.

Another object relates to the provision 30 of ball bearings for insuring rotation of the drilling tool after each operation.

Other objects will appear from the following description taken in connection with the accompanying drawings, in which—

35 Figure 1 is a longitudinal section of the assembled tool holding device attached to the lower end of an oil well wire rope;

Figure 2 shows a side elevation thereof;

Figure 3 shows a section taken on the line 3—3 of Figure 1;

Figure 4 shows a section taken on the line 4—4 of Figure 1, and

Figure 5 shows a partial longitudinal section of the device when held stiff.

45 Referring to the drawings there is shown a wire rope 10 which is intended to extend through a shaft of the well and is connected at the surface of the ground to a source of power (not shown). The lower end of the 50 rope extends into the interior of a socket casing or shell 11 having portions 12, 13 of restricted diameter and portions 14, 16 of relatively enlarged diameter. The interior of the socket 11 is recessed to form a shoulder 17 near the upper portion thereof.

For gripping the rope there is provided

an elongated mandrel or piston 20 having an aperture extending lengthwise therethrough. The wire rope 10 extends through an aperture which is of such configuration as to 60 provide a snug fit of the rope therein. In the lower portion of the mandrel 20 the aperture is gradually enlarged to form a tapered recess 21 and is provided with a series of shoulders, such as 22, 22. The 65 strands of the rope 10 are thus permitted to unravel somewhat in the enlarged portion 21 of the aperture and to engage the shoulders 22, 22. The upper portion of the mandrel 20 has an integral sleeve 23 extending 70 upwardly around the rope 10 and within the socket 11, forming with the main portion of the mandrel 20 a shoulder 24.

For permitting relative movement between the mandrel 20 and the socket 11 75 there may be provided a ball bearing comprising a recessed race member 30 and a cone race member 31 co-operating therewith and retained in position by the shoulder 17 of the socket 11 and shoulder 24 of the 80 mandrel 20 respectively.

The wall of the enlarged portion 14 of the socket 11 is provided with a plurality of sand release holes, such as 33 for permitting the escape of earth, sand and slime 85 and insuring a clearer tool socket. An adjusting lock plug 34 is screw threaded into the interior of the socket 11, the lower end thereof being provided with a rectangular recess 35 with which a usual plug wrench 90 may engage. The lower end of the socket 11 is tapered to form a tool joint 36 and is provided with usual tool joint screw threads whereby the tool, such as a drilling bit, may be securely held therein for the drilling 95 operation.

The tool holding device of Figure 1 may be assembled by inserting the race member 30 into the interior of the socket 11 so as to engage the shoulder 17, then inserting 100 the race member 31 so as to engage the first named race member and then running the wire rope through the aperture extending through the upper portion of the socket 11 105 and the two race members. The end of the wire rope 10 is then inserted into the interior of the mandrel 20 and the strands un-twisted so as to engage the shoulders 22, 22. The mandrel 20 is then drawn back into 110 the socket 11 and into the position shown in Figure 1. The lock plug 34 is secured into the socket 11 by means of a suitable plug

wrench and the tool inserted into the lower end of the socket.

The mandrel 20 is thus free to rotate with respect to the socket 11 in the operation of the device and the longitudinal movement of the parts is positively limited by the adjustment of the lock plug 34. Such limitation of longitudinal movement effectively prevents blunting of the mandrel 20 and the distortion of the mandrel which results from excessive play between the parts of the device.

It will also be seen that there is provided because of the free motion of the bearing surfaces, a positive means for eliminating such earth, sand or slime as may fall down through the well, these foreign materials being ejected through the sand release holes 35. Excessive wear of the bearing surfaces due to such foreign materials is thus effectively prevented.

Referring to Figure 5 which shows a modification of a portion of Figure 1, there is provided in the space between the upper face of the lock plug 34 and the lower end 25 of the mandrel 20 a jamb plug 50 whereby rotation of the jamb plug during assembly thereof exerts an upward pressure on the mandrel sufficient to prevent relative turning of the parts. By screwing the lock plug 34 in tightly a stiff socket is provided.

Thus it will be seen that I have provided a tool holding device which may be rendered swivelling or stiff as may be desired. The projection of the mandrel through to the top end of the socket is of great importance as it minimizes wear on the wire rope and greatly increases the life thereof.

Furthermore, the arrangement of the parts is such that there is substantially no play between the mandrel and the socket so that distortion of the mandrel which would lead to jamming thereof within the socket is effectively prevented. The number of sand releasing holes in the socket of the present invention is greatly increased relative to the sockets of the prior art without materially weakening the socket, thus insuring a clearer tool socket.

Various changes or modifications may be employed without departing from the spirit of the invention. It is understood therefore that the scope of the invention is not to be limited to the particular embodiment here

selected for the purpose of illustration, reference being had to the appended claims for 55 that purpose.

Having thus described my invention, what I claim and desire to secure by Letters Patent is:—

1. The combination with a mandrel for 60 tools adapted to drill into the earth's surface, said mandrel having a stepped bore extending longitudinally therethrough provided with interiorly disposed shoulders for engaging a rope, of a socket arranged to 65 enclose the mandrel and having free rotatable movement with respect thereto, and positive means for limiting the longitudinal movement of the socket with respect to the mandrel.

2. A rope socket swivel for well drilling apparatus, comprising in combination a casing having a cylindrical chamber at one end and a reduced bore at the other forming a shoulder, the wall of said casing having a 75 plurality of perforations to permit discharge of foreign materials from within said chamber, a rotary piston comprising a head and a stem positioned in the chamber and bore respectively and having a stepped bore 80 extending longitudinally therethrough for engaging a rope, a separable conical friction reducing bearing between the head of the piston and the shoulder of the casing, and means movable independently of the 85 piston for effectively preventing relative movement between the casing and the piston.

3. In a swivel for tools adapted to drill into the earth's surface, the combination 90 with a shell having a cylindrical chamber at one end and a reduced bore at the other end forming a shoulder, the wall of said shell having a plurality of perforations to permit egress of foreign materials from within said chamber, of a rotatable member having a head and a stem positioned within said chamber and bore respectively, said member having a stepped bore extending longitudinally therethrough for engaging a rope, and a two part friction reducing bearing between the head of the rotatable member and the shoulder of the shell.

Signed at Frontera, Tabasco, Mexico, this 12 day of September, A. D. 1923.

DANIEL SHONQUIST.
